UNITED STATES PATENT OFFICE.

GLENN E. TURNER, OF LATHAM, KANSAS.

TEMPER SCREW.

Application filed June 13, 1921. Serial No. 477,113.

To all whom it may concern:

Be it known that I, GLENN E. TURNER, a citizen of the United States, residing at Latham, in the county of Butler and State of Kansas, have invented certain new and useful Improvements in Temper Screws, of which the following is a specification.

This invention relates to the art of well-boring and more particularly to improvements in temper screws used in well drilling rigs.

One object of the invention is to provide a handle for a temper screw having means for locking the temper screw against rotation relative to its supporting reins.

Another object of the invention is to provide a handle for a temper screw which may be readily assembled therewith or removed therefrom, together with means for interlocking the handle to the screw.

A further object of the invention is to provide an improvement in the detachable connection between the temper screw and its supporting reins.

These and such other objects as may hereinafter appear are attained by the novel construction, combination and arrangement of parts to be hereinafter specifically described and claimed.

Reference will now be had to the accompanying drawings forming a part of this specification, wherein:

Figure 1 is a front elevation of a portion of a temper screw having my improvements embodied therein.

Figure 2 is a sectional view of a portion of the handle showing the means for interlocking the handle to the screw and the means for locking the screw against rotation relative to the supporting reins.

Figure 3 is a sectional view taken on the line 3-3 of Figure 1 and looking in the direction of the arrows.

Throughout the following detailed description and on the several figures of the drawing, similar parts are referred to by like reference characters.

Referring to the drawings, the reference numeral 1 designates the reins having at their lower ends clamping jaws 2 having screw-engagement with the temper screw 3. Surrounding the jaws 2 is a collar 4 having a bolt 5 extending through the free ends thereof upon which is journaled a lever 6 having an eccentric or cam portion 7 for co-operation with one of the jaws 2, a set-screw

8 being adjustably mounted in the eccentric for limiting the movement of the lever in one direction. When the lever 6 is in the full line position shown in Figure 1, the jaws 2 are in their normal closed position and the temper screw 3 is adjusted in the usual manner by rotation thereof. When, however, the lever is moved to the dotted line position the jaws 2 may be opened sufficiently to enable the workman to raise the temper screw to any desired position whereupon the lever will be returned to full line position to close the jaws tightly about the screw. It will be noted that the set-screw 8 may be so adjusted that the engaging point 9 on the cam portion 7 of the lever will be above the pivot point 5 when the lever is in full line position. In other words the set-screw arrests the movement of the lever when it has moved slightly past dead center in the direction to close the jaws whereby the lever will be locked in this position. The provision of the set-screw avoids the necessity of weighting the free end of the lever and providing a positive latch for holding it in operative position as shown, for instance, in the patent by Baldwin, No. 476,721.

The reference numeral 10 designates the swivel which is supported on the head 11 at the lower end of the temper screw by a ball-bearing 12. The swivel 10 is provided with downwardly extending projections 10' to which is fastened by screws 13 a plate 14 carrying a rod 15 which extends completely through the screw from end-to-end thereof and is fastened at its upper end to the reins 1 in such manner as to prevent relative rotation between the reins and the swivel. The connection between the upper end of the rod 15 and the reins 1 is by means of a block 15' which extends transversely between the reins and has grooves in its ends to receive the reins whereby the block is free to slide up and down on the reins as guides but is held from rotation relative to the reins. The upper end of the rod passes through an opening in the block 15' and is keyed thereto so that the rod cannot rotate with respect to the block. Lock-nuts are provided on the screw-threaded end of the rod to securely fasten the block to the rod.

The handle bar which is designated by the reference numeral 16 is provided with a hub 17 rotatably mounted upon a cylindrical portion 18 of the temper screw. One of the arms 19 of the handle bar has a screw-thread-

ed end 20 engaging in a screw-threaded socket 21 in the hub 17. The inner end of the arm 19 is adapted to engage the cylindrical portion 18 so that by turning the arm 19 the handle bar 16 may be clamped to the temper screw or released therefrom. Adjacent its screw-threaded end the arm 19 is provided with a faceted wrench-engaging portion 22. Rotatably and slidably mounted upon the opposite end of the arm 19 is a sleeve 23 having a knurled surface and provided with pins 24 engaging in spiral slots 25 in the arm whereby rotation of the sleeve causes it to move axially of the arm. The arm 19 is provided with a bore 26 and extending through the bore 26 and the opening 27 in the head of the sleeve 23 is a rod 28. The end of the rod projecting through the sleeve 23 is provided with a nut 29. The opposite end of the rod projects through a bore 30 in the temper screw 3 forming a continuation of the bore 26 in the arm 19 and normally engages an opening 31 in the rod 15 to lock the temper screw against rotation relative to its supporting reins. The bore 26 of the arm is enlarged at the threaded end thereof as indicated at 32 and located in the enlarged bore is a coil spring 33 engaging at one end against the bottom 30 of the bore 32 and at its other end against a shoulder or enlargement 34 on the rod 28. The coil spring 33 tends to normally maintain the rod 28 in interlocking engagement with the opening 31 in the rod 15. To release the rod 28 from its interlocking engagement with the rod 15 the sleeve 23 is rotated in a direction to cause it to move outwardly with respect to the arm 19, the nut 29 on the rod 28 engaging with the head of the sleeve and causing the rod to move outwardly with the sleeve and its end to be withdrawn from the opening 31 with which it is engaged, whereupon the handle bar 16 is free to rotate the temper screw. Thus is provided a simple construction whereby the handle bar may be assembled with and locked to the temper screw, and these parts readily unlocked and disassembled when desired, and whereby the temper screw may be locked against rotation relative to its supporting reins.

Having thus described my invention, what I claim as new and desire to secure by Letters Patent is:

55. 1. In a device of the class described, a temper screw, reins having jaws at their free ends for engagement with said screw, means movable to one position for holding said jaws closed and in operative engagement with said screw and movable to another position to permit said jaws to be separated for disengaging them from said screw, and adjustable means engageable with the reins incident to the jaw closing movement of said means for limiting the move-

ment of said first-mentioned means in the direction to close the jaws.

2. In a device of the class described, a temper screw, reins having jaws at their free ends for engagement with said screw, a member engaging one of said jaws, a lever pivotally connected to said member and provided with a cam portion for cooperation with the other of said jaws to hold the latter closed and in operative engagement with said screw in one position of said lever and permitting the jaws to be separated for disengaging them from said screw in another position thereof, and an adjustable abutment to arrest movement of the lever in the direction to close the jaws after said lever has passed dead center.

3. In a device of the class described, a temper screw, supporting means therefor in which said temper screw is rotatably adjustable, a handle carried by said temper screw, and means carried in part by said handle for locking said temper screw against rotation relative to said supporting means.

4. In a device of the class described, a temper screw, supporting means therefor in which said temper screw is rotatably adjustable, a handle carried by said temper screw, and means for locking said temper screw against rotation relative to said supporting means, comprising a member connected to said supporting means and extending through said temper screw, a member slidably mounted in said handle and adapted to interlock with said first-mentioned member, and means for moving said slideable member into and out of engagement with said first-mentioned member.

5. In a device of the class described, a temper screw, supporting means therefor in which said temper screw is rotatably adjustable, a handle carried by said temper screw, and means for locking said temper screw against rotation relative to said supporting means, comprising a member connected to said supporting means and extending through said temper screw, a member slidably mounted in said handle and adapted to interlock with said first-mentioned member, means for moving said slideable member into engagement with said first-mentioned member, and separate means for moving said slideable member out of engagement with said first-mentioned member.

6. In a device of the class described, a temper screw, supporting means therefor in which said temper screw is rotatably adjustable, a handle carried by said temper screw, and means for locking said temper screw against rotation relative to said supporting means comprising a member connected to said supporting means and extending through said temper screw, a member slidably mounted in said handle and adapted to interlock with said first-men-

tioned member, a spring for moving said 55
slidable member into engagement with said
first-mentioned member, and a member ro-
tatably and slidably mounted upon said
handle for moving said slidale member out
of engagement with said first-mentioned
member.

7. In a device of the class described, a
temper screw, supporting means therefor
in which said temper screw is rotatably ad-
justable, a handle carried by said temper
screw and having a bore therein, and means
for locking said temper screw against ro-
tation relative to said supporting means
comprising a member connected to said sup-
porting means and extending through said
temper screw, a rod slidably mounted in
the bore in said handle and in a bore in
said temper screw and adapted to interlock
20 with said member, a coil spring in said bore
in said handle and engaging said rod for
moving the latter into engagement with said
member, and a sleeve rotatably and slidably
25 mounted upon said handle for moving said
rod out of engagement with said member.

8. In a device of the class described, a
temper screw, supporting means therefor in
which said temper screw is rotatably ad-
justable, a handle carried by said temper
screw and having a bore extending there-
30 through from end-to-end, said bore being
enlarged at the inner end of said handle,
said temper screw having a bore forming a
continuation of the bore in said handle, and
means for locking said temper screw against
35 rotation relative to said supporting means
comprising a member connected to said sup-
porting means and extending through said
temper screw, a rod slidably mounted in the
40 bores in said handle and temper screw and
provided with a shoulder in the enlarged
portion of the bore in said handle, a coil
spring in said enlarged bore having one
45 edge engaging the bottom of said bore and
the other end engaging said shoulder for
forcing said rod into engagement with said
member, and means for moving said rod out
of engagement with said member.

9. In a device of the class described, a
50 temper screw, supporting means therefor in
which said temper screw is rotatably ad-
justable, a handle carried by said temper

screw, and means for locking said temper
screw against rotation relative to said sup-
porting means, comprising a member con-
55 nected to said supporting means and ex-
tending through said temper screw, a mem-
ber slidably mounted in said handle and
adapted to interlock with said first-men-
tioned member, means for moving said slid-
60 able member into engagement with said
first-mentioned member, a sleeve rotatably
mounted on the free end of said handle and
having a head at its outer end provided with
an opening therein for the passage of said
65 slidale member, said slidale member hav-
ing a shoulder on its outer end engaging
the outer face of said head, and a pin on
said sleeve engaging in a spiral slot in said
70 handle whereby rotation of said sleeve causes
the same to move axially of said handle and
thereby move said slidale member to dis-
engage it from said first-mentioned member.

10. In a device of the class described, a
temper screw, supporting reins therefor in
which said temper screw is rotatably ad-
justable, a swivel mounted on said temper
screw, means carried by said swivel and en-
75 gaging said reins, whereby to prevent rela-
tive rotation between said reins and swivel,
and means carried by said temper screw and
adapted for engagement with said last-men-
tioned means for locking said temper screw
80 against rotation relative to said supporting
reins and said swivel.

11. In a device of the class described, a
temper screw, supporting reins therefor in
which said temper screw is rotatably ad-
justable, a swivel mounted upon said temper
screw and in which said temper screw is
90 adapted to rotate, a member carried by said
swivel and extending through said temper
screw and connected to said reins for pre-
venting relative rotation between said swivel
and reins, a handle carried by said temper
95 screw, means slidably mounted in said han-
dle and adapted to interlock with said mem-
ber to lock said temper screw against ro-
tation relative to said swivel and reins, and
means for moving said slidale means into
100 and out of engagement with said member.

In testimony whereof I affix my signa-
ture.

GLENN E. TURNERY.
